FIG.8.

UNITED STATES PATENT OFFICE.

HUBERT SYDNEY TURNER, OF SAN DIEGO, CALIFORNIA.

TELEPHONE-SWITCHBOARD OPERATING AND SIGNALING DEVICE AND SYSTEM.

1,175,488.

Specification of Letters Patent. Patented Mar. 14, 1916.

Application filed June 23, 1911. Serial No. 634,893.

To all whom it may concern:

Be it known that I, HUBERT SYDNEY TURNER, a naturalized citizen of the United States of America, residing at San Diego, in the county of San Diego and State of California, have invented a new and useful Telephone-Switchboard Operating and Signaling Device and System, of which the following is a specification.

10 This invention relates to apparatus for and the operation of telephone switchboard signaling systems, and involves a special form of jack-plug provided with insulated contact plates and means for breaking the 15 circuit of the ordinary flexible connecting wires of the plug without disturbing the electrical contacting connections of the plug and the jack with which the plug is engaged; contact devices carried on the hand 20 of the telephone switchboard operator, adapted to contact with the insulated plates of the plug when said plug is properly grasped and included in circuit with the operator's transmitter and receiver; a signal 25 device having special features of construction and operation also included in circuit with the operator's hand carried contacts adapted to automatically give a clear signal to the telephone user connected up by the 30 plug inserted in the jack at the instant the operator completes connection and during the time of communication with such subscriber or user; and push buttons or keys conveniently located to be controlled by the 35 feet, or other available part of the operator's body, for cutting in on the line, represented by the jack in which the plug may be inserted, a ringing or calling device to operate only on the line represented by one of the 40 two jack-plugs attached to any wires which may be used for interconnecting the various telephone stations.

A practical embodiment of my invention is illustrated in the accompanying drawings, 45 in which:

Figure 1 is a longitudinal sectional view of an improved jack plug. Fig. 2 is a transverse section of the same, taken on the line 2, 2, Fig. 1. Fig. 3 is a side view of the jack-plug. Figs. 4, 5 and 6 are enlarged views of a contact device adapted to be carried on the hand of a telephone switchboard operator, showing respectively a plan view of the device with its cover removed, a vertical section and a plan view showing the cover attached. Fig. 7 illustrates two contact de-

vices attached to a holding means by which they may be securely fastened to the hand of an operator. Fig. 8 illustrates a signaling apparatus adapted to be connected to a subscriber's circuit by the hand carried contacts of the operator, and: Fig. 9 illustrates the various parts or devices of this telephone switchboard operating and signaling apparatus and system, showing an arrangement 6 of the wire connections.

The improved jack-plug has a two part metallic casing A and B separately fastened to a central insulating block C by the flush caps Q' and N' of the screws Q and N. The section A is permanently electrically connected to the jack contact H of the plug by the central rod G, block E and screw M; and the section B is permanently electrically connected to the other jack contact O of the 7 plug by the sleeve D and screw P. The contacts H and O and their metallic connections with the insulated sections A and B are, of course, thoroughly insulated. The usual connecting wires 1 and 2 of the plug pass 8 through a split cap R fitted by a groove formed therein over the ends of the sections A and B, and serving to clamp the wires 1 and 2 between corrugated faces of the cap, when the sections are fastened in position by 9 their screws Q and N. The connecting wire 1 goes to the screw N and is in communication with the outer contact O of the plug; the other connecting wire 2 passes to a screw L which passes through the insulating block C and holds one end of a spring K against 10 said block, the other end of the spring being in contact with a conical pointed sleeve F fitted to slide on the rod G, and pressed toward the spring K by a spiral spring J placed in its interior. Electrical connection is thus made between wire 2 and jack contact H of the plug and permits breaking the connection of the circuit of the plug wires with the jack contacts of the plug without disturbing the electrical connections of the insulated sections A and B with the contacts H and O. This is accomplished through the medium of ring I of insulating material fitted to slide on the sections A and B and connected to the sleeve F by screws T', T² which pass through the ring I into the ends of studs S', S² extending outwardly from the sleeve F between the edges of the sections A and B, as shown at Fig. 2, said edges being cut away (Fig. 3) to insure non-contact of the studs with the sections A and B.

The ring I when slid toward the end of the plug carrying the superficial jack contacts, moves the sleeve F away from spring K and so breaks the circuit of one of the plug connecting wires.

Another feature of the invention comprises devices to be worn preferably on the thumb and a finger of the operator. These contacts are fastened to strips extending 10 from a wrist band Z² of suitable material, by which they may be properly held on the hands of the operator, or they may be carried on a complete glove. The thumb contact consists of contact points V', V² electrically joined to the connecting screws W', W² to which are attached wires extending to the wrist band, a spring U normally out of contact with the points V', V² but caused to connect said points when depressed by 15 the pressure plug Y that extends through the top plate X' of a hollow casing or box of insulating material containing the spring and its co-acting parts. Screws, Fig. 6, hold the top plate X' in position and also hold a 20 supplemental base X² between which and the base of the box may be clamped an elastic band or finger stall X³, adapted to securely hold the contact device on the thumb or finger. The other contact device consists 25 of a fine and flexible wire Z suitably secured to a finger stall Z' connected to the wrist band Z².

Another feature coöperating with those described consists of a signaling device, Fig. 35 8, comprising two electro-magnets a and b having corresponding ends of their windings connected by wire 15, and the other ends extended respectively to the posts g' and g² which by lines 3, 4 (Figs. 9 and 10) 40 connect with one of the points V' or V² of the respective thumb contacts. The other ones of said points V' or V² are connected to line 7, Fig. 9. A bell c is arranged to be struck by hammers carried on the ends of 45 the spring armature levers a' and b' of the magnets a and b which levers are connected by line 16. An electromagnetic vibrating device has its magnet e included in a local circuit including a battery 13, the vibrator 50 armature lever 18, contact point d' or d², armature levers a' or b', line 16, line 17 and posts h' and h². There is a telephone transmitter t included in a line extending from line 15 to post i. The armature lever 18 is 55 delicate in its operation and carries a hammer 20 of rubber or other sound deadening material, and by the contact screw f is so adjusted that the sound effect produced on the bell c is a metallic murmur and not a ring. All of these devices are contained in a box j of suitable resonant material.

When a plug of the character shown, attached to one end of a cord which is connected at the other end to the answering 60 jack of a subscriber's line, is grasped by the

hand contacts of the operator, the contact Y depresses the spring U and a local circuit is completed comprising contact point V', screw W', conductor 7, primary of induction coil n, battery 8, operator's transmitter o, binding post i of signal device j, transmitter t, magnet a or b, binding post g' or g², conductor 3 or 4 (according to which hand the operator has used), screw W², contact point V² and spring U. Magnet a or b 70 is energized and by armature a' or b' imparts a single stroke on bell c, the vibrations of which set up in the transmitter t a pulsatory current and thus, by causing variations in resistance of the circuit, alternating currents are set up in the secondary of induction coil n which, by conductor 9, push button l' or l², conductor 11 or 12, to other hand contact Z that is in contact with one of the plates A or B of the plug, the 75 other plate being in contact with contact Y. Another circuit is thus completed including a subscriber's receiver through the conducting cord of the plug, the jack to one side of the subscriber's line, the other side of subscriber's line, the other line contact in the answering jack and plug, the other talking strand in conducting cord, spring U of the hand contact and conductor 7 to the other end of the secondary coil. By this means a 80 single tone, similar to that produced by the bell c, is heard by the calling subscriber as soon as the operator has answered the call by inserting a plug in the subscriber's answering jack and grasping the specially designed cord-connected plug. This signal notifies the calling subscriber that he is in communication with the operator and may without delay make his requirements known 85 without special request by the operator since the operator's receiver p is bridged across the line 7 and 9 and is in circuit with the secondary of the induction coil n. Now with the plugs properly placed for conversation 90 between two subscribers, privacy is fully assured for should the operator or any one at 95 central attempt to "listen in" (which can only be done by the plates of an active plug being grasped by the hand contacts) the subscribers will be made aware of this by 100 a murmur or sound of special character sent through the line, because such act on the part of the operator energizes one of the magnets a or b, as before described, and a 105 continuous current through either of them 110 will close a local circuit, by armature a' or b' being held in contact with point d' or d², including the magnet e post h', battery 13, post h², conductor 17, armature and point in contact, wire 19, contact point f, make and 115 break spring actuated armature lever 18 and wire connecting lever post to the magnet. The muffled hammer 20 of lever 18 by rapid 120 vibrations produces the distinctive murmur 125 sounds before described.

The means for electrically cutting in on a line (represented by the jack in which a plug is inserted) whereby a signaling or other ringing device *k*, Fig. 9, of ordinary construction adapted to sound the subscriber's telephone call bell on the line included in the operating circuit by one of the two jack-plugs attached to conducting cords for interconnecting telephone stations, comprises push buttons *l'* and *l²*, or similar connecting devices, adapted to be operated by the feet or other available parts of the operator's body. A suitable arrangement is as shown. The normal contacts of these push buttons are joined together by wire 9, and the operating contacts by the wire 10 connected to a terminal of the signaling device *k* whose other terminal connects with line 7. The operator's receiver *p* is included in a circuit between lines 9 and 7 as is also the secondary of the induction coil *n*. The push buttons or contact devices *l'*, *l²*, are by the wires 11 and 12 connected to contacts *Z* of the right and left hand contact operating devices *m'* and *m²*. The wire plan, in general, of this telephone switchboard operating and signaling system is shown at Fig. 9.

From the foregoing it will be seen that either the right or left hand or both hands, and the right or left foot or both feet, of the operator may be used in the manipulation of the apparatus of the system; so a description of the functions of one of the hand contact devices, the one marked *m'* for instance, in conjunction with the other devices described will answer for both.

When a plug is grasped by the operator and inserted in the jack and the sliding ring *I* of the plug pressed forward the call bell of the called subscriber will be actuated by the ringing device *k* on depression of the key *l'*, the circuit then being from the contact plate of the plug touched by the hand contact *Z*, line 11, line 10, to *k*, from *k* by lines 7 and 5 to the contact point *Y* which closes circuit with the other contact plate of the plug. The ringing current is prevented from entering the calling subscriber's line by manipulating of the sliding ring *I*. Now when the operator releases key *l'* the circuit then includes contact *Z*, line 9, operator's receiver *p*, line 7, primary of the induction coil *n*, battery 8, operator's transmitter *o*, line 14, post *i*, of the signaling device *j*, line 2, transmitter *t*, line 15, magnet *a*, post *g'*, and line 3 to hand contact *Y*, and also the secondary of the induction coil *n* by lines 9 and 7 to contact *Y*. The operator may, by manipulating the sliding ring *I* of a plug, break the circuit of the connecting wire of said plug without interfering with the plug connections to the jack, enabling the operator to signal, etc., over the subscriber's line represented only by the jack in which the manipulated plug is inserted.

The circuit including the apparatus of the device *j*, the operator's transmitter *o*, battery 8 and primary of the induction coil *n* is normally broken at the points *V'*, *V²* of the hand contact, and the various devices in this circuit are brought into action only by the contact plug *Y* being depressed to cause the spring *U* to contact with the points *V'*, *V²*.

I claim:

1. In a telephone signaling apparatus, hand borne contacts, an automatically operating pulsatory current signaling device, comprising an electro-magnet, a gong actuated thereby, a source of electricity and a circuit closer included in a local circuit, a telephone transmitter and an electro-magnet adapted to actuate said circuit closer, said transmitter and the circuit closing electromagnet being permanently included in a circuit with the hand borne contacts and the primary of an induction coil and a jack plug provided with insulated plate contacts on the hand grasping portion thereof independent of but connected to the jack contacts of the plug, whereby a calling subscriber is, by the action of the signaling device, notified that he has the central operator's attention and may immediately communicate with him as soon as the operator grasps the subscriber's plug with the hand borne contacts.

2. In a telephone signaling apparatus, hand borne contacts, an automatically operating signaling device comprising a telephone transmitter, an electro-magnet adapted by its armature to sound a gong, a source of electricity and the primary of an induction coil permanently included in an electric circuit with said contacts and a jack plug provided with insulated plate contacts on the hand grasping portion thereof independent of but connected to the jack contacts of the plug, whereby the hand contacts circuit is, by the hand contacts and the plate contacts of the plug, connected up to the jack circuit to which the plug is connected, whereby the calling subscriber is immediately, by the action of the signaling device, notified that he has the central operator's attention and may communicate with him.

3. In a telephone signaling apparatus, hand borne contacts, an automatically operating signaling device included in an electric circuit with said contacts, and a jack plug provided with insulated plate contacts independent of, but connected to the jack contacts of the plug and means on the jack plug adapted to be manipulated by the operator's hand for breaking the circuit of one of the plug connecting wires without disturbing the connections of the plug jack contacts, whereby the operator's circuit may be included in circuit with one only of two talking subscribers.

4. In a telephone signaling apparatus,

- 4
- hand borne contacts, an automatically operating signaling device comprising a transmitter, the operator's transmitter and receiver permanently included in electric circuits 45
 5 with said contacts and a jack plug provided with insulated plate contacts independent of but connected to the jack contacts of the plug and means on the jack plug adapted to be manipulated by the 50
 10 operator's hand for breaking the circuit of one of the plug connecting wires without disturbing the connections of the plug jack contacts.
 5. In a telephone signaling apparatus, 55
 15 hand borne contacts, circuit lines extending therefrom, one of which is normally open, means for closing this circuit, a signaling device included in an electric circuit with said contacts and a jack plug provided with
 20 insulated plate contacts independent of but connected to the jack contacts of the plug, whereby when a plug is grasped by the hand to bring the hand contacts and the plate contacts of the plug together the normally open
 25 hand contact closing means is actuated and the hand contact circuit is connected up with the jack circuit to which the plug is connected.
 6. In a telephone signaling apparatus, 60
 30 hand borne contacts, circuit lines connected therewith, one of which is normally open, means for closing this circuit carried by the hand, a push button or switch adapted to be operated by the operator's foot or other
 35 available part of the body, a subscriber's signaling or calling device included in the hand contacts circuit when the push button or switch is operated, and a jack plug provided with insulated plate contacts inde- 65
 40 pendent of but connected with the jack contacts of the plug, whereby when a plug is grasped by the hand to bring the hand contacts and the plate contacts of the plug
 connected up with the jack circuit to which the plug is connected.

together the normally open hand contact closing means is actuated and the hand contact circuit is connected up with the jack circuit to which the plug is connected. 45

7. In a telephone signaling apparatus, hand borne contacts, an automatically operating signaling device, the operator's transmitter and receiver, an electric battery and the primary of an induction coil permanently included in a branch of the circuit to one of the hand contacts, the secondary of the induction coil included in a branch of the circuit to the 55
 other hand contact and a jack plug provided with insulated plate contacts independent of but connected to the jack contacts of the plug, whereby the hand contacts circuit is, by the hand contacts and the 60 plate contacts of the plug, connected up with the jack circuit to which the plug is connected.

8. In a telephone signaling apparatus, 65
 hand borne contacts, an automatically operating signaling device permanently included in an electric circuit with said contacts, said signaling device including a bell, a signal giving magnet, a vibrator adapted to produce a subdued buzzing sound in circuit with a 70
 local battery and a circuit closer actuated by the signal giving magnet, and a jack plug provided with insulated plate contacts independent of but connected to the jack contacts of the plug, whereby the hand contacts circuit is, by the hand contacts and the plate contacts of the plug, connected up 75
 with the jack circuit to which the plug is connected.

In testimony whereof, I have hereunto 80
 subscribed my name.

HUBERT SYDNEY TURNER.
